(57) **CLAIM**

The ornamental design for a separatable food packaging, as shown and described.

DESCRIPTION

FIG. 1 is a perspective view of a separatable food packaging showing my new design in environmental use;

FIG. 2 is a front view of the separatable food packaging;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines shown in FIG. 1 represent unclaimed subject matter and form no part of the claimed design.

The dotted lines shown in FIGS. 1, 6 and 7 represent perforation and form part of the claimed design.
